(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is another rear perspective view thereof, showing the mobile phone where a graphic is displayed;

FIG. 10 is another front perspective view thereof, showing the mobile phone of FIG. 1 in an alternate configuration;

FIG. 11 is a front view of FIG. 10;

FIG. 12 is a rear view of FIG. 10;

FIG. 13 is a left side view FIG. 10;

FIG. 14 is a right side view FIG. 10;

FIG. 15 is a top plan view FIG. 10;

FIG. 16 is a bottom plan view FIG. 10; and,

FIG. 17 is a rear perspective view FIG. 10.

The broken lines in the drawings illustrate portions of the mobile phone that form no part of the claimed design. The

(Continued)

other broken lines in FIG. 9, showing a graphic, represent environmental subject matter only and form no part of the claimed design.
